ANTIAIRCRAFT FIRE CONTROL APPARATUS

Ernst von Segebaden, Drottningholm, and Ragnar Österdahl, Stora Essingen, Sweden, assignors to Asenco Aktiebolag, Stockholm, Sweden, a Swedish joint-stock company

Application July 3, 1944, Serial No. 543,386
In Sweden July 6, 1943

7 Claims. (Cl. 235—61.5)

This invention relates to an anti-aircraft fire control apparatus, and it is an object of our invention to provide simplified and otherwise improved mechanical means for computing data for the firing of the missile. Another object of our invention consists in the provision of means for preventing obstacles caused by interference of certain elements of the apparatus due to their ability to swing through any angles whatever. With these and other objects not specifically mentioned in view, the invention consists in certain constructions and combinations which will be hereinafter fully described and then specifically set forth in the claims hereunto appended.

In the accompanying drawings:

Fig. 1 is a diagram illustrating the theory underlying the invention, with special reference to an arrangement for correction of parallax;

Fig. 2 is a perspective view of an apparatus embodying the invention;

Fig. 3 is a sectional view on the line III—III of Fig. 1;

Fig. 4 is a sectional view on the line IV—IV of Fig. 3;

Fig. 5 is a sectional view on the line V—V of Fig. 2;

Fig. 6 is a sectional view on an enlarged scale on the line VI—VI of Fig. 2;

Fig. 7 is a sectional view on an enlarged scale on the line VII—VII of Fig. 2;

Fig. 8 is a view, partly in section, on the VIII—VIII of Fig. 7; and

Fig. 9 is a diagram illustrating the theory underlying the invention with special reference to the employment of sound locators.

Referring to Fig. 1 of the drawings, the assumption is made that a sighting instrument is positioned at the observing station M at a horizontal distance b from the battery B for firing at an aerial target F. By means of the sighting instrument an arm 1 (Fig. 2) is adjusted into an angular position equal to the angle of inclination β of the line of sight MF to the aerial target F. The arm 1 is secured to a rotatable hollow shaft 2 into which is inserted another rotatable shaft 3 which by means of a bevel gear 4 is connected to a range screw 5 having a slider 6 which is slidably mounted in the arm 1. The slider 6 is by means of a pin 7 pivoted to another slider 8 which is displaceable in a vertical guide 9 of a horizontally disposed sliding rod 10. In the slider 8 is vertically movable still another slider 11, to which is secured a pin 12 parallel to the shaft 2. The slider 11 is mounted on a vertical lead screw 13 the spindle 14 of which is

inserted into a worm wheel 15, which is rotatably journaled on the sliding rod 10. The spindle 14 is vertically displaceable but not rotatable relative to the worm wheel 15. The worm wheel 15 meshes with a worm 17 which is displaceably but not rotatably mounted on a spindle 19 which is provided with a handle 18. The spindle 19 is rotary journaled in the frame of the apparatus but not displaceable relative same. By turning the handle the slider 11 can be displaced vertically in the slider 8, so that the vertical distance between the pins 7 and 12 will be adjusted.

The pin 12 engages in a longitudinal slot 20 of another arm 21, which is secured to a hollow shaft 23. The shaft 23 is rotatably journaled on a carriage 22 and a toothed segment 24 is secured to said shaft. The carriage 22 is slidably mounted in a horizontal guide 80, and the centres of the shafts 2 and 23 are positioned in the same horizontal plane. The toothed segment 24 meshes with a pinion 25, which is secured to another pinion 26 that meshes with a toothed rotatable drum 27 rotatably journaled in the frame of the apparatus. The swing of the arm 21 will by this arrangement be transmitted to the drum 27. Into the hollow shaft 23 is inserted a rotatable shaft 28, to which is secured a pinion 29. The pinion 29 meshes with a rack 30, which also meshes with a toothed disc 31 fixed to the pin 12. The shaft 28 is by means of a gear 32 connected to another shaft 33, which by means of a pinion 34 transmits rotary movements of the shaft 28 to a toothed drum 35 rotatably journaled in the frame of the apparatus. Thus the rotary movements of drum 35 indicate variations of the effective length of the arm 21, i. e. the distance between the centres of the pin 12 and the shaft 28. This rotary movement of the drum 35 is not disturbed by the swing of the arm 21 since the pinion 31 does not rotate when the arm 21 is turned.

When the effective length of the arm 1, i. e. the distance between the centres of the pin 7 and the shaft 2, by rotating the shaft 3 is adjusted to correspond to the range s of the target F and the arm 1 by rotating the shaft 2 is adjusted to incline to the horizontal plane at an angle equal to the angle of elevation β the horizontal component $MF_0=a$ of the line of sight MF is obtained. This value is by the displacement of the rod 10 transmitted to a mechanism for computing the remaining data of the horizontal triangle MBF₀. Said computing mechanism has two arms 36 and 37 connected to oppositely disposed hollow shafts 38 and 39, respectively, and

positioned side by side, so that they are free to swing through any desired angles (one complete revolution e. g.). Thus the swing of the arm 36 is unobstructed by the shaft 39, and the swing of the arm 37 is unobstructed by the shaft 38. The axes of the shafts 38 and 39 are located in one and the same horizontal plane, and they are in Fig. 1 represented by M and F_0 , respectively, so that the distance between them $MF_0=a$. Thus the centres of the shafts 37 and 39 are collinear when the pin 7 occupies a position right above the shaft 2, i. e. when $\beta=90^\circ$. The shaft 39 is parallel to the shaft 38 and rotatably journalled in a downwardly directed bracket 40 of the sliding rod 10. The arms 36 and 37 are pivotally interconnected by a pin 41 the centre of which is in Fig. 1 represented by F_0 . The direction of the line MF_0 relative to the direction of origin (the direction of the base line MB) is obtained by rotating a shaft 42 proportionately to the angle α . This angular adjustment is by a gear 43 transmitted to the shaft 38 and further to the arm 36. By rotating another shaft 44 the distance between the centres of the shaft 38 and the pin 41, i. e. the effective length of the arm 36 is adjusted to indicate the horizontal distance b (the length of the base line) between the observing station M and the battery B. For that purpose a range screw 35 is rotatably journalled in the arm 36 longitudinally thereof and screwed into a slider 46 carrying the pin 41. The screw 45 is by a bevel gear 47 connected to a shaft 48 rotary journalled in the hollow shaft 38 and by a gear 64 connected to the shaft 44.

By thus introducing into the triangle computing mechanism the values of a , b and α the horizontal component $BF_0=a'$ of the range between the target F and the battery B will be ascertained by said mechanism as it is proportional to the distance between the centres of the shaft 39 and the pin 41. Furthermore, the triangle computing mechanism gives the direction of the line BF_0 as the adjustment of the angular position of the arm 37 is by the shaft 39, a bevel gear 65 secured to same, another bevel gear 66 secured to a shaft 49 rotatably journalled in the bracket 40, and a pinion 50 rotatably journalled in the frame of the apparatus transmitted to a toothed drum 51. The angle of inclination of the arm 37 to the horizontal plane is δ and

$$\gamma=\alpha-\delta$$

Adjustments of the distance of the pin 41 from the shaft 39, i. e. the adjustment of the distance a' are transmitted to the carriage 22. For that purpose a slider 53 is pivotally mounted on the pin 41 and displaceable in a slot 52 in the arm 37. The slider 53 is rigidly secured to a rack 54 meshing with a pinion 55 secured to a shaft 56, rotatably journalled in the hollow shaft 39. The shaft 56 is connected to a gear wheel 57 which meshes with a rack 58 secured to the carriage 22. Thus the adjustment of the pin 41 longitudinally of the arm 37 will by the rack 54 and other elements be transmitted to the carriage 22. The ratio of dimensions and transmission is chosen so that the pin 12 is positioned right above the shaft 23 if $a'=0$. If the pins 7 and 12 are positioned at one and the same height above the horizontal plane including the centres of the shafts 2 and 23 the distance between the centres of the pin 12 and the shaft 23, i. e. the effective length of the arm 21 will correspond to the range s' between the battery B and the target

F. Thus a' the horizontal component of s' and the altitudinal angle β' is the angle of inclination of the arm 21. The values of s' and s ' are transmitted to and by the drums 27 and 35, respectively. As mentioned above the angle γ has also been ascertained by the triangle computing mechanism and, consequently, the range between the target F and the battery B as well as the direction of the line of sight BF to the target have been ascertained. The values of direction and range are e. g. by electrical means transmitted from the fire control instrument to the battery at B.

The foregoing description was made under the presumption that the sighting instrument at M and the battery at B were on a level with each other. Otherwise, a correction has to be made. If the assumption be made that the battery is positioned at B' (Fig. 1), i. e. at a lower level than the instrument at M, the corresponding correction can be introduced into the instrument by downward transversal displacement of the shaft 23, so that the difference of height of the centres of the shafts 2 and 23 corresponds to the vertical distance h' . The same result will, however, be obtained in a simplified manner, viz, by displacing the pin 12 upwardly, so that the difference of height of the pins 7 and 12 will be h' . Thereby on maintaining a' unvariable other values s'' and β'' of the range and direction will be obtained.

The relative adjustment of heights of the pins 7 and 12 can also for causes of inclined flight be utilized for correction of varying altitude of the target F, if the spindle 19 is controlled by appropriate altitude computing means.

The rack 58 has to transmit from the triangle computing mechanism to the carriage 22 such displacements only relative to the sliding rod 10 that depend on the longitudinal displacement of said rack, i. e. variations of the distance between the pin 41 and the shaft 39. Hence the swing of the arm 37 must not cause the relative longitudinal movements of the sliding rod 10 and rack 58. Therefore, the gear wheel 57 is not directly connected to the shaft 39 but by means of an epicyclic gear. As shown in Fig. 7, this epicyclic gear has two sun wheels 59 and 60 of equal dimensions and two pairs of planet pinions 61, 62 of equal dimensions which intermesh by pairs and are rotatably journalled on pins 63 secured to the gear wheel 57. One of the planet pinions 61 of each pair meshes with the sun wheel 59, and the other planet pinion 62 meshes with the sun wheel 60. The sun wheel 59 is secured to the shaft 56, and the sun wheel 60 is idly journalled on the same shaft and rigidly connected to a bevel gear wheel 67 of the same size as the gear wheel 65 and meshing with the bevel gear wheel 66.

Assuming that the shaft 37 is turned without variation of its effective length, i. e. without longitudinal displacement of the rack 54 the shafts 39 and 56 are rotated, and thereby the sun wheel 59 and the gear wheel 65 rotate correspondingly. Thereby the sun wheel 60 is by means of the gear 66, 67 rotated through the same angle but in the opposite direction. Thus the sun wheels 59 and 60 rotate the planet pinions 61 and 62, respectively, in opposite directions, so that they roll upon each other without rotating the gear wheel 57. If instead thereof the arm 37 does not swing and its effective length a' is adjusted the shaft 56 only is rotated. Then the sun wheel 60 is steady whilst the sun wheel 59 is rotated and drives the planet pinions 61 which in turn

rotate the planet pinions 62. Then the planet pinions 62 roll upon the steady sun wheel 60 and drive the gear wheel 57. Thereby the gear wheel 57 is turned through an angle being the half of the rotary movement of the gear wheel 55. Therefore the diameter of the gear wheel 57 is twice the diameter of the gear wheel 55, so that a certain displacement of the rack 54 will cause the same displacement of the rack 58.

For the purpose of obviating disturbance of the adjustments of the lead screws 5 and 45 depending on swing of the arms 1 and 36, respectively, an epicyclic gear similar to that described above is provided between the shaft 3 and the gear 4 and between the shafts 44 and 48.

The apparatus described with reference to Fig. 2 can also be utilized for ascertaining the angle of lead, i. e. point of impact when firing at a movable aerial target or for ascertaining the actual position of such a target at the moment of observation by means of a sound locator. The application of the invention when using a sound locator is illustrated diagrammatically in Fig. 9.

In Fig. 9 the assumption is made that an air-craft flies at a straight course at a constant speed and altitude. The sound locator is positioned at L. If the point A represents the position of the air-craft at the time the sound was emitted, which is heard at L, then the air-craft will be at point O by the time the sound reaches the sound locator. The direction of the line LO is to be ascertained by means of the apparatus as shown in Fig. 2. The range LO is of no interest in this case. Therefore the distance AL is assumed to be constant, viz. equal to the velocity c of sound. Consequently, the distance f between the points A and O represents the speed of the air-craft. The effective length of the arm 1 of Fig. 2 represents this value. Thus the range screw 5 is adjusted to indicate constant measure of range. The vertical projections of the points A and O on the horizontal plane including the point L are denoted by A' and O', respectively. Thus the triangle LA'O' is horizontal, and the triangles LAA' and LOO' are vertical. AA' and OO' represent the constant altitude h . By means of a sound locator the shaft 2 (Figs. 2 and 3) is rotated so that the arm 1 is adjusted into an angle of inclination μ (Fig. 9) to the horizontal plane. Thereby the length a of the line LA' is ascertained and supplied by the sliding rod 10 to the triangle computing mechanism, so that the distance between the centres of the shafts 38 and 39 will be a . By rotating the shaft 42 the arm 36 is adjusted so that its angle of inclination to the horizontal plane including the centres of the shafts 37 and 39 will be ψ . The angle ψ represents the course of the air-craft and is computed by certain means such as that described in the Swedish patent application No. 4681/1943. Furthermore the estimated speed f of the air-craft is introduced into the triangle computing mechanism. By rotating the shaft 44 the screw 45 is adjusted so that the effective length of the arm 36 represents the speed f . Thereby the data of a , f , and ψ have been introduced into the triangle computing mechanism, so that also the value of o can be obtained, which is represented by the effective length of the arm 37, viz. the distance between the centres of the pin 41 and the shaft 39. Furthermore, the angle φ is ascertained, which is indicated by the inclination of the arm 37 to the horizontal plane. The angle of inclination φ is indicated by the drum 51 as explained in the foregoing. The value 75

of the horizontal component o of the range between the air-craft in its actual position at O and the sound locator at L is in the same manner as described in the foregoing transmitted to the carriage 22, so that the horizontal component of the effective length of the arm 21 will be o . As the altitude of the air-craft is constant the pins 7 and 23 occupy the same position of height h . The sides h and o of the triangle LOO' having been ascertained the angle of elevation ϵ of the line LO will also be ascertained by transmitting the inclination of the arm 21 to the horizontal plane to the drum 27, as described hereinbefore.

If the side LA' of the triangle LA'O' is directed at an angle ω to a line of direction of origin, then the total angle of deflection, i. e. the bearing angle

$$\sigma = \omega + \varphi$$

Thus, by means of the apparatus as shown in Fig. 2 the angle of deflection δ as well as the angle of elevation ϵ of the actual line of sight to the air-craft have been ascertained.

The function of the apparatus as described with reference to Fig. 9 may also be utilized for ascertaining the angle of lead when firing at an air-craft.

In the operation of the apparatus as shown in Fig. 2 it may occur that one or several of the range values represented in Fig. 9 will be equal or approximately equal to zero. Thus if the aerial target is at rest the value f is zero, and if said target consists of an air-craft in zenith when emitting a sound $\mu=90^\circ$ and, consequently, the value of a is zero. Furthermore, it might occur that the air-craft is approaching in the azimuthal plane at such a speed that L and O' coincide. In such case the values of ψ and o are zero.

The apparatus as shown in Fig. 2 is so constructed that it admits coincidence of the points L and A'. In such case the shafts 38 and 39 are collinear. The apparatus admits also the introduction of $f=0$. In such case the pin 41 and the shaft 38 are collinear. But if the value of o is at the same time zero the arm 37 is supported at one point only, so that it will obtain an unstable equilibrium, and its direction will be indefinite. Even though the value o exceeds zero slightly the effective length of the arm 37 will be too short to enable transmitting with sufficient power of angular adjustments to the arm 21 and drum 27. Therefore, the arm 37 has an abutment 68 adapted to arrest the pin 41 when approaching the shaft 39 and tending to pass a minimum of o corresponding to a maximum value of ϵ . However, if ϵ would exceed this value when the value of ψ is zero, then the value of μ increases simultaneously. This increase is directed by the sound locator, which cannot be arrested suddenly. Therefore the arm 1 is yieldingly connected to the shaft 2, so that the arm 1 can be arrested when the pin 41 engages the abutment 68 whilst the shaft 2 continues its angular movement corresponding to the increase of the angle of elevation μ introduced by the sound locator. As soon as ψ , μ or f have been changed so that the minimum value of o is again exceeded, the interference of the pin 41 with the abutment 68 is released and the arm 1 is yieldingly moved into its correct angular position on the shaft 2 on engaging an abutment, as will be described hereinafter.

Interference might also occur by decrease of μ when the arms 36 and 37 are swung into parallel positions, whereat the shaft 39 is positioned

between the pin 41 and the shaft 38. Then on decreasement of μ , i. e. increasement of a the abutment 68 approaches the pin 41 until interference occurs. Therefore the arm 1 is yieldingly connected to the shaft 2 also in an angular direction opposite to that mentioned above. When this interference is finished the correct angular position of the arm 1 on the shaft 2 is reestablished by a spring which turns the arm into yielding engagement with an abutment, as will be described hereinafter.

The above-mentioned yielding connection of the arm 1 with the shaft 2 is obtained by means of two tension springs 70 and 71 one end of which is connected to a drum 72 fixed to the shaft 2. The other end of each spring 70 and 71 is connected to sliders 76 and 77, respectively, which are displaceable each in a circumferential slot 73 and 74, respectively, that extend all around the drum 72 except at a longitudinal interconnection bar 75 serving as a driver and an abutment for the sliders 76 and 77. The arm 1 is loosely mounted on the shaft 2 and carries a pin 78, which engages in the space between the sliders 76 and 77, when they abut the bar 75.

On interference, viz. arrested swing of the arm 1 in the direction P', for instance, the rotary movement of the shaft 2 continues in said direction. Then the drum 72 displaces by means of the bar 75 the slider 77 in the same direction, whilst the slider 76 will still, under the influence of increasing yielding power exerted by the spring 70, be held in engagement with the pin 78 on the arm 1 being steady by interference. When the interference is interrupted the arm 1 is released, and thereby the slider 76 engaging the pin 78 will under the influence of the spring 70 swing the arm 1 until its pin 1 engages the slider 77. Thus, in this case the slider 77 serves as an abutment arresting the arm 1 in a correct angular position relative to the shaft 2, viz. the angular position defined by the rotation of the shaft 2 as directed by the sound locator. This spring coupling acts in the same manner, if interference occurs when the shaft 2 is rotated in the opposite direction, viz. the direction P''. Thereby the slider 76 will be displaced in that direction, and the slider 77 will on interrupted interference serve as a driver to correct the position of the arm 1 by moving the pin 78 into engagement with the slider 76 now serving as an abutment.

Interference might also occur if the pin 41 hits the abutment because of decreasement of ψ . Such interference will consequently not be caused by movements of the arm 1, wherefore the springs 70 and 71 acting upon the arm 1 cannot in this case cause yielding engagement of the pin 41 with the abutment 68. Therefore yielding engagement is in this case obtained thereby that the shaft 42 is connected to its control handle 80 by means of a spring coupling 79.

Interference might also occur when the speed f of the target is changed if the target moves in the azimuthal plane, viz. when the centres of the pin 41 and the shafts 38 and 39 are located in one and the same plane and the pin 41 approaches the shaft 39. Such interference is made yielding by the arrangement of a spring coupling 81 between the shaft 44 and its control handle 82.

We claim:

1. In an apparatus for gun fire control, means for trigonometrically computing ballistic values, comprising a triangle computing mechanism hav-

ing two computing members adapted to represent two sides of a triangle, a pivot slidably interconnecting said members, and two parallel and transversely displaceable rotatable shafts each of which carries one of said members, the distance between the centres of said shafts, representing the third side of said triangle, said members being interconnected side by side at said pivot, and said shafts projecting from their respective arms in opposite directions, so that each of said members is free to swing unobstructed by the shaft of the other member.

2. In a fire control apparatus for anti-aircraft guns, a vector mechanism having elements adjustable according to the angles of azimuth of two intersecting vertical sight planes, a mechanical vector, means to adjust said mechanical vector angularly according to the angle of elevation of the target in one of said vertical sight planes, means to transmit from said mechanical vector to said vector mechanism a datum of horizontal range of the target, a second mechanical vector pivotally connected to the first mechanical vector and being adjustable angularly according to the angle of elevation of the target in the other vertical sight plane, and means for transmitting from said vector mechanism to said second mechanical vector a datum of the horizontal range of the target in said other vertical plane of sight.

3. In a fire control apparatus for anti-aircraft guns, a vector mechanism having elements adjustable according to the angles of azimuth of two intersecting vertical sight planes, a mechanical vector, means to adjust said mechanical vector angularly according to the angle of elevation of the target in one of said vertical sight planes, means to transmit from said mechanical vector to said vector mechanism a datum of horizontal range of the target, a second mechanical vector pivotally connected to the first mechanical vector and being adjusted angularly according to the angle of elevation of the target in the other vertical sight plane, and means for transmitting from said vector mechanism to said second mechanical vector a datum of the horizontal range of the target in said other vertical plane of sight, said vector mechanism comprising two pivotally interconnected range members, one of said range members being connected by an epicyclic gear to said second mechanical vector, whereby said vector is adjustable independently of angular movements of said range member.

4. In a fire control apparatus for anti-aircraft guns, a vector mechanism having elements adjustable according to the angles of azimuth of two intersecting vertical sight planes, a mechanical vector, means to adjust said mechanical vector angularly according to the angle of elevation of the target in one of said vertical sight planes, means to transmit from said mechanical vector to said vector mechanism a datum of horizontal range of the target, a second mechanical vector pivotally connected to the first mechanical vector and being adjustable angularly according to the angle of elevation of the target in the other vertical sight plane, and means for transmitting from said vector mechanism to said second mechanical vector a datum of the horizontal range of the target in said other vertical plane of sight, the pivotal connection between said mechanical vectors being adjustable according to different altitudes in said two vertical sight planes.

5. In an apparatus for gun fire control, means for trigonometrically computing ballistic values, comprising a triangle computing mechanism

61.5

2,394,827

5

having two computing members adapted to represent two sides of a triangle, a pivot slidably interconnecting said members, and two parallel and transversely displaceable rotatable shafts each of which carries one of said members, the distance between the centres of said shafts, representing the third side of said triangle, said members being interconnected side by side at said pivot, and said shafts projecting from their respective arms in opposite directions, so that each of said members is free to swing unobstructed by the shaft of the other member, one of said computing members having an abutment for limiting relative movements of said pivot and the shaft carrying said member.

6. In a fire control apparatus for anti-aircraft guns, a vector mechanism having elements adjustable according to the angles of azimuth of two intersecting vertical sight planes, a mechanical vector, means to adjust said mechanical vector angularly according to the angle of elevation of the target in one of said vertical sight planes, means to transmit from said mechanical vector to said vector mechanism a datum of horizontal range of the target, a second mechanical vector pivotally connected to the first mechanical vector and being adjustable angularly according to the angle of elevation of the target in the other vertical sight plane, means for trans-

mitting from said vector mechanism to said second mechanical vector a datum of the horizontal range of the target in said other vertical plane of sight, one of said elements of said vector mechanism having an abutment for limiting relative movements of said elements, and yielding means for transmitting data to said vector mechanism.

7. In a fire control apparatus for anti-aircraft guns, a vector mechanism having elements adjustable according to the angles of azimuth of two intersecting vertical sight planes, a primary mechanical vector adjustable angularly according to the angle of elevation of the target in one of said vertical sight planes, means to transmit from said mechanical vector to said vector mechanism a datum of horizontal range of the target, a secondary mechanical vector pivotally connected to said primary mechanical vector and being adjustable angularly according to the angle of elevation of the target in the other vertical sight plane, means for transmitting from said vector mechanism to said secondary mechanical vector a datum of the horizontal range of the target in said other vertical plane of sight, and yielding driving means for said angular adjustment of said primary mechanical vector.
